E. S. HUMPHREYS.
HIGH FREQUENCY ELECTRICAL APPLIANCE.
FILED DEC. 27, 1920.

UNITED STATES PATENT OFFICE.

EDWIN S. HUMPHREYS, OF CLEVELAND, OHIO, ASSIGNOR TO THE ROGERS ELECTRIC LABORATORIES COMPANY, OF CLEVELAND, OHIO, A CORPORATION.

HIGH-FREQUENCY ELECTRICAL APPLIANCE.

Application filed December 27, 1920. Serial No. 433,296.

To all whom it may concern:

Be it known that I, EDWIN S. HUMPHREYS, a citizen of the United States, residing at Cleveland, in the county of Cuyahoga and State of Ohio, have invented certain new and useful Improvements in a High-Frequency Electrical Appliance, of which the following is a specification.

My invention relates to a therapeutical 10 appliance in which a high-frequency electrical current is produced and discharged through an electrode secured within one end thereof, and the appliance is especially constructed to promote the following results; 15 to permit a free circulation of air through the appliance to keep the body and parts therein cool during operations; to allow the working parts and end cap to be readily removed and handled as a unit; and to 20 establish spring seating relations between the parts and the body to prevent looseness, displacement and poor contact.

In the drawings accompanying this application, Fig. 1 is a side view, partly in 25 section, of my improved appliance, and Fig. 2 is a view at right angles to Fig. 1 on line 2—2, thereof. Fig. 3 is a cross section on line 3—3 of Fig. 2, and Fig. 4 is a cross section on line 4—4, of Fig. 1. Fig. 5 is 30 a view of the front end of the appliance. Fig. 6 is a diagram of the electric circuit used in the appliance.

The invention comprises a cylindrical body 2 of hard rubber having a reduced 35 nose portion 3 provided with a ribbed and fluted central opening 4 which communicates with the round hollow interior or large chamber 5 extending the full length of the body. A clamping holder or socket 40 6 is confined within the inner shouldered portion of opening 4, and this socket is adapted to receive and grip the stem of any suitable high-frequency electrode introduced into opening 4. The opposite end of 45 body 2 is adapted to be closed or partly closed by a screw cap 8 having a double saddle 9 bolted upon its inner face directly opposite a central opening 10 therein. A current interrupter is mounted on saddle 50 9, and this interrupter comprises an adjusting contact screw 11 adapted to project through opening 10 into screw-engagement with a threaded opening in saddle 9 and opposite a vibratory armature 12 mounted 55 on one head 13 of the interrupter coil 14.

The heads of coil 14 consist of round flat pieces 13—13 of insulating material corresponding in diameter to the round chamber 5 so as to fit snugly therein at diametrically opposite points. However, these pieces 13 60 are cut away or flattened oppositely to provide air spaces 15 opposite body 2, and the round body of the coil is at one side of the center of the heads and of less diameter than chamber 5 to permit air to circulate 65 around the coil and through body 2. The air enters chamber 5 through opening 10 and several other air entrances 16 in screw cap 8, and passes out of the fluted portions of opening 4 around the stem of the electrode which is of approximately the same diameter as socket 6.

A high-frequency coil 17, comprising a primary and secondary winding is placed in advance of coil 14, and it also comprises 75 round flat pieces 18 at its opposite ends with portions removed at the edges to seat said coil 17 centrally within chamber 4 and so that the air may circulate freely around the same. The core 19 of coil 17 projects 80 a sufficient distance beyond the front end thereof so that it will contact with socket 8 and at the same time space the front piece 18 of the coil apart from the body to permit the air to pass into fluted opening 4. The 85 two coils 14 and 17 are jointly supported upon saddle 9 and connected together in a yielding manner by a pair of tie rods 20—20' which also serve as electrical conductors in the working circuits for the coils, 90 see Fig. 6. Thus, rod 20 extends lengthwise at one side of coil 17 and through both of its end pieces 13—13, and is fastened at one end by a nut 21 to one arm of saddle 9, see Fig. 1, while the opposite end 22 is 95 bent to extend at an angle to the major portion across the front end of the coil to the opposite side where a straight terminal portion 23 is again bent to project through and seat the rear end piece 18 of coil 17 where 100 one end of the secondary winding 24 may be connected therewith. The second tie rod 20' is fashioned like the first and placed on the opposite side of coil 14 with its angular portion 25 extending cross-wise to the 105 angular portion 22 of rod 20, and a straight terminal portion 26 is also formed at the end of this cross portion 25 so that it may project through and seat end piece 18 and connect with the opposite end of winding 110

24, see Fig. 1. Rod 20' is connected with a lead-in wire and rod 20 with saddle 9, and thus both are placed in the electric circuit. Furthermore, the crossing portions of these 5 two rods provide a yielding spring connection between the two coils 14 and 17 so that when end cap 8 is screwed into the open end of body 2 and contact is made between core 19 and socket 6 all said parts 10 are placed under spring compression and firmly seated and held in their respective working positions within the body. A condenser 28 is mounted at one side of coil 14 and bound to it by a piece of tape 29, and 15 one way of electrically connecting the various parts herein described in an operative circuit is shown in Fig. 6, but no claim is made herein for the circuit nor is it intended that the invention should be limited 20 to such a specific circuit.

What I claim is:

1. A high-frequency electrical appliance, comprising a tubular body adapted to hold an electrode, an electrical means adapted to 25 produce a high-frequency electric current supported lengthwise within said body in spaced relation the full length of the inner walls thereof to permit free circulation of air around said means, and said body having air intake and exit openings at its opposite ends adapted to permit free circulation of air through said body where the electrode is held therein.

2. A high-frequency electrical appliance, comprising a tubular body having a fluted opening at one end adapted to hold an electrode, and electrical means supported within said body apart from the walls thereof to permit air to circulate around the same 40 and through said fluted opening.

3. A high frequency electrical appliance, comprising a tubular body, and high-frequency electrical means removably confined under spring compression with said body.

4. A high frequency electrical appliance, comprising a tubular body, and a set of coils removably seated in spring-connection within said body.

5. A high frequency electrical appliance, comprising a tubular body adapted to receive an electrode within one end thereof, and a removable cap at the opposite end of

said body having a set of coils jointly supported thereon and secured in end seating relation with each other.

6. A high frequency electrical appliance, comprising a tubular body having a detachable screw cap at one end thereof and rods extending from said cap and coils supported upon said rods.

7. A high frequency electrical appliance, comprising a tubular electrode-holder having a removable end cap provided with a saddle, and a current interrupter and a high-frequency coil jointly secured together end 65 for end upon said saddle.

8. A high-frequency electrical appliance, comprising a tubular electrode-holder having a detachable end cap, a pair of rigid conductors secured to said cap, and a current interrupter and a high-frequency coil supported upon said conductors.

9. A high-frequency electrical appliance, comprising a tubular body, an end cap for said body, a pair of conductor rods supported upon said cap having spring extremities, and separate coils supported upon said rods upon opposite sides of said spring extremities.

10. A high frequency electrical appliance, comprising a cylindrical body having a socket at one end adapted to hold an electrode, a removable cap at the opposite end of said body having an adjusting screw extending into said body, and an interrupter and a high-frequency coil rigidly secured together end for end and jointly supported in a rigid position upon said cap opposite said screw.

11. A high frequency electrical appliance, comprising a cylindrical body having a fluted opening at one end, an electrode terminal confined within said opening, a removable cap for the opposite end of said body having a saddle, an interrupter coil secured to said saddle, conducting rods on 95 opposite sides of said coil and supported by said saddle, and a high frequency coil connected with said rods having a contact at one end adapted to engage said terminal.

Signed at Cleveland, in the county of 100 Cuyahoga, and State of Ohio, this 14 day of December, 1920.

EDWIN S. HUMPHREYS.
